UNITED STATES PATENT OFFICE.

DAVID N. BUTTERFIELD, OF NEW BOSTON, NEW HAMPSHIRE, ASSIGNOR OF ONE-HALF TO HENRY F. WILLARD, OF CAMBRIDGE, MASSACHUSETTS.

DESK.

SPECIFICATION forming part of Letters Patent No. 310,877, dated January 20, 1835.

Application filed May 5, 1834. (No model.)

To all whom it may concern:

Be it known that I, DAVID N. BUTTERFIELD, a citizen of the United States, residing at New Boston, in the county of Hillsborough, State 5 of New Hampshire, have invented a certain new and useful Improvement in Desks for Children, of which the following is a specification.

The object of my invention is to so construct 10 the supports for a desk that they may be readily removed or replaced, also that when the supports are separated from the desk all of the parts forming the supports can be separated and packed in a small space. I attain these 15 objects by the mechanism illustrated in the accompanying drawings, in which—

Figure 1 is a perspective view of my desk complete; Fig. 2, a perspective view showing the supports separated from the body of the 20 desk and packed thereon.

In the drawings, A represents the body of the desk. B B' B B' are the supports of the desk. These supports are framed together near their center so as to form an X, as shown. 25 The upper ends have attached to them a metal plate, C. This plate C adds greatly to the strength of the supports, and serves as a device for attaching the supports to the body of the desks. The attaching device consists of

the plate C, having a nick, D' D', at each end, 30 so that it (the plate) can slide in under the heads of the screws D D, and thus be held in position. The cross-bar H terminates at each end in a pintle and screw, the pintle passing entirely through the legs at the joint, and is 35 secured by a nut, K, Fig. 1. This construction of the supporting parts admits of their being removed from the body of the desk without the use of tools, it only being necessary to unscrew the nuts K by the hand; then 40 by springing the supports a little way in the direction of the length of the desk the bar H can be removed; then by sliding the supports inwardly toward the center of the desk the plate C will slide out from the screws D D and 45 the supports will be entirely separated from the body of the desk.

I claim as my invention—

In a child's desk, the combination of the cross-bar H, the supports B B', and the plate 50 C, nicked as shown, with the screws D D and the body A of the desk, all constructed substantially as described, and for the purpose set forth.

DAVID N. BUTTERFIELD.
